US00D640346S

(12) **United States Design Patent**
Sheppard et al.

(10) **Patent No.:** **US D640,346 S**
(45) **Date of Patent:** **** Jun. 21, 2011**

(54) **WATER FILTRATION CONTAINER**

(75) Inventors: **Nasahn Adam Sheppard**, Mill Valley, CA (US); **Dominik Heinz Langhammer**, San Francisco, CA (US); **Joern Vicari**, Brooklyn, NY (US); **Maarten Dinger**, San Francisco, CA (US); **Shannon Leigh Koy**, Berkeley, CA (US)

(73) Assignee: **The Procter & Gamble Company**, Cincinnati, OH (US)

(**) Term: **14 Years**

(21) Appl. No.: **29/346,767**

(22) Filed: **Nov. 5, 2009**

(51) LOC (9) Cl. **23-01**

(52) U.S. Cl. **D23/209**

(58) **Field of Classification Search** D23/207, D23/209, 212; D7/300, 312, 316-319; 210/85, 210/266, 282, 321.6, 470, 482; 222/130, 222/131, 189.07, 465.1; 215/6; 220/521

(57) **CLAIM**

The ornamental design for a water filtration container, as shown and described.

DESCRIPTION

FIG. 1 is a perspective view of an embodiment of a water filtration container illustrating our new design;

FIG. 2 is a left side elevational view thereof;

FIG. 3 is a right side elevational view thereof;

FIG. 4 is a front side elevational view thereof;

FIG. 5 is a back side elevational view thereof;

FIG. 6 is a top planar view thereof; and,

FIG. 7 is a bottom planar view thereof.

The broken lines in the drawings represent portions of the water filtration container that form no part of the claimed design.
